UNITED STATES PATENT OFFICE.

BARNETT RUBENSTEIN, OF CHICAGO, ILLINOIS.

DESIGN FOR A SPREADER MEMBER FOR THE BARS OF AUTOMOBILE-TOPS.

41,597.

Specification for Design.

Patented July 18, 1911.

Application filed March 7, 1910. Serial No. 547,946. Term of patent 3½ years.

To all whom it may concern:

Be it known that I, BARNETT RUBENSTEIN, a citizen of the United States, and resident of Chicago, in the county of Cook and State of Illinois, have invented a new, original, and ornamental Design for a Spreader Member for the Bars of Automobile-Tops, of which the following is a specification, reference being had to the accompanying drawing, forming part thereof.

In these drawings, Figure 1 is a per-

spective view of a spreader member for the bars of automobile tops. Fig. 2 is an edge view of the same.

I claim:

The ornamental design for a spreader member for the bars of an automobile top, as shown.

BARNETT RUBENSTEIN.
